UNITED STATES PATENT OFFICE

ALVIN S. MANCIE, OF SOMERVILLE, MASSACHUSETTS, ASSIGNOR TO COMSTOCK & WES-COTT, INC., OF BOSTON, MASSACHUSETTS, A CORPORATION OF MASSACHUSETTS

COMBUSTION APPARATUS

Application filed February 3, 1931. Serial No. 513,142.

This invention relates to combustion apparatus for burning fluid fuel, such for example as gas, which is mixed with a combustion supporting medium such as air.

The present invention provides a burner which is particularly adapted to operate for long continued periods of time without requiring attention and without necessitating skilled care, while affording protection against dangerous abnormal conditions. Accordingly this burner is particularly suited to employment in household apparatus where safety, dependability, and freedom from complications are highly desirable characteristics. This burner may be employed for example in refrigerating apparatus such as an absorption system or a system of the character disclosed in Patent No. 1,761,551 to Eastman A. Weaver, wherein a liquid propellant is vaporized, the propellant vapor being effective in pumping refrigerant through a refrigerant circuit. In apparatus of this character, it is desirable to have a burner which is adapted to operate continuously and which has incorporated therein or combined therewith suitable safety means to protect the user of the apparatus from the results of abnormal conditions such as an abnormal increase in gas pressure, backfiring, an interruption of gas flow for any reason, and various other accidental occurrences.

To permit these desirable results, the present invention provides a burner, the combustion end of which is normally enclosed within a casing so that danger of accidental extinguishing of the flame or of ignition of surrounding articles is avoided. In order to permit these desirable results and yet to permit initial ignition of the fuel stream, the burner is arranged so that it may be removed from the casing under certain conditions, while locking means retains the burner within the casing and prevents its removal therefrom when combustion is continuing in the normal manner, thus inexperienced persons are prevented from tampering with or removing the burner when ignition is taking place. Furthermore, this locking means also prevents the burner from being removed after ignition is interrupted, until sufficient

time has elapsed for collected gas to be exhausted into the flue, thus avoiding premature removal of the burner and the consequent possibility of the introduction of a dangerous quantity of the combustible mixture into the room.

Furthermore the device is provided with a valve and control means adapted automatically to interrupt the flow of fuel to the burner if combustion is for any reason interrupted, this control means permitting the continued flow of fuel as long as the burner tip remains at the ordinary operating temperature.

A further aspect of the invention relates to the arrangement of means for interrupting the flow of fuel to the burner if combustion occurs adjoining the outer end of the burner or adjoining the air ports rather than at the burner tip. Furthermore, the flow of gas is automatically interrupted when the temperature of combustion reaches a very high point due to abnormal gas flow or due to the denuding of the boiler with which the burner is associated. Thus, for example, when the cooling effect of the liquid within the boiler is removed, the temperature of the region surrounding the burner tip rapidly rises so that the automatic control means is actuated to interrupt further fuel flow and combustion is thus stopped; thus damage to the boiler is avoided and attention is called to the defect in the system with which the boiler is associated. Further features of the invention relate to details of construction which permit the provision of a simple, effective and dependable combustion apparatus and which are adapted to insure the satisfactory operation of the apparatus under normal conditions and its automatic interruption under abnormal conditions, thus safeguarding the user of the apparatus.

In the accompanying drawings:

Fig. 1 is a central vertical sectional view of the combustion apparatus and the support or portion of the casing upon which it is normally mounted;

Fig. 2 is an end elevation of the outer portion of the apparatus and the support shown in Fig. 1;

Fig. 3 is a side elevational view of the outer end of the combustion apparatus and of its support;

Fig. 4 is a view partly in elevation and partly in section of a part of the apparatus showing the inner end of the burner tube and the latch to hold the supporting plate in its frame;

Fig. 5 is a view similar to Fig. 1 showing the control means in the normal operating position;

Fig. 6 is a sectional detail of a portion of the control means and related parts showing the same in the position occupied when the 15 temperature of the burner tip reaches an abnormally high point;

Fig. 7 is a view partly in section and partly in elevation of a portion of the burner assembly and the support showing the burner being reengaged with the support;

Fig. 8 is a view similar to Fig. 4, showing an optional arrangement of parts;

Fig. 9 is an enlarged sectional detail of the automatic means for interrupting the 25 flow of fuel in case of backfiring;

Fig. 10 is an elevational detail of a part of the assembly shown in Fig. 8;

Fig. 11 is a section indicated by line 11—11 of Fig. 9;

Fig. 12 is a perspective view of the heat responsive element which is employed in the assembly shown in Figs. 8, 9 and 10;

Fig. 13 is a section indicated by line 13—13 of Fig. 3;

Fig. 14 is an end elevation of the burner; and

Fig. 15 is a sectional detail of the control means, being a section on the same plane as that of Fig. 1, but upon a larger scale.

Referring to the accompanying drawings, and first more particularly to Fig. 1, the numeral 1 designates the wall of a casing which may receive the combustion apparatus that more particularly forms the subject matter of the present invention. For example, this casing may be formed of metal and may substantially enclose the boiler and adjoining parts of a refrigerating apparatus of the type disclosed in the above identified patent to Eastman A. Weaver. An annular support 2 may be disposed about an opening in the casing wall 1 and may receive the combustion apparatus or burner designated in general by the numeral 3. The burner includes a substantially circular plate 4 with an annular flange 5 that normally has an interfitting engagement with a corresponding flange 6 upon the support 2. A burner tube 9 projects inwardly from the flange 4 and its end forms a burner tip which is provided with a grid 10.

A metal bushing 12 may be threaded into an engagement with an opening in the plate 4 and may fit within the adjoining end of tube 9, being secured thereto by a fastening screw 13. Preferably tube 9 may be formed

of metal of low heat conductivity, such as nichrome. A cylindrical casing 15 may have one end disposed about the flange 6 of support 2 and may substantially enclose the major portion of tube 9, the inner end of the casing being continued in a tapered portion 16 which terminates in a cylindrical end portion 17. Preferably the cylindrical jacket portion 15 is formed of heat-resistive material of low heat conductivity such as mica. 70

An inlet casting 19 is preferably secured to the outer face of plate 4 by fastening means such as screws 20 (Fig. 14). This casting is provided with a depending portion 22 having an inlet passage 23 which is connected to a flexible fuel supply duct 24. A bore 25 forms an enlarged continuation of passage 23 and extends upwardly to the upper surface of the casting 19 adjoining plate 4. The bore 25 not only forms a continuation of the inlet passage 23 but also provides a valve casing or chamber. A bushing 27 is threaded into the upper part of the bore 25, and the spindle 28 of a supply valve 29 is slidably received in bushing 27. A coiled compression spring 30' is disposed between the lower end of bushing 27 and a shoulder upon the valve and holds a metal washer against a packing washer 26 that is pressed against the spindle 28 and the bushing 27. This spring also tends to hold valve 29 against a seat provided by the mouth of inlet passage 23. A passage 33 connects the valve chamber 25 with a large cylindrical recess 30 at the upper part of casting 19. The upper portion of this recess 30 has internal threads with which a plug 31 is normally engaged. A vent member 32 has a cylindrical end portion threaded into engagement with an opening communicating with the side of chamber 30 and provides a small outlet opening or vent 35 (Fig. 9) which is aligned with the central axis of burner tube 9. The bushing 12 which extends into the burner tube 9 and is screwed into plate 4 has an outwardly extending portion disposed about the member 32 and provides a series of air ports 36 adjoining vent 35. As shown, the intermediate part of the bushing 12 may be shaped to provide a throat 37. 80

When the valve 29 is in its open position, fuel from the flexible supply pipe 24 may flow upwardly through the inlet passage 23, the valve chamber 25 and passage 33 to the chamber 30 and thus through the vent 35 into the bushing 12. Air entering through ports 36 mixes with the fuel, and the resulting mixture flows through the bushing 12 and burner tube 9 to the grid 10 at the burner tip where combustion normally takes place. 90

The main control means which is associated with the valve 29 may comprise a control plate 39 having an end portion loosely engaging a recess 40 in the casting 19 (Fig. 7) and having a slot engaging a portion 42 of the valve spindle 27 which has a reduced 100

diameter, the upper end of the spindle terminating in a head 43 which may engage the upper face of the control plate 39. Plate 39 projects through a slot 44 (Fig. 4) in the plate 4 and its inner end supports a metal block 45 (Fig. 15) with an extension 46 providing a cylindrical bore in which a coil spring 47 is disposed, this spring normally urging a ball 48 outwardly into engagement with an inturned lip 49 at the outer end of the bore.

A metal collar 50 is mounted on the end of the tube 9 and a bi-metallic, heat responsive element 51 is secured to a depending extension 52 of collar 50. The opposite end of the heat responsive element 51 is connected by fastening elements such as screws 53 to the control bar 54. The latter is shown more particularly in Fig. 1 and may comprise a hollow shell 56 formed of metal of low heat conductivity such as nichrome, while reinforcing blocks 58 and 59 may be disposed in the ends of shell 56. Fastening screws 53 extend through openings in the block 58, while a suitable rivet 60' may secure the block 59 to the opposite end of the shell 56. The end of block 59 preferably projects beyond the shell and is pointed as shown in Fig. 1.

When the combustion apparatus is cold and not operating, the heat responsive element 51 may be in the position shown in Fig. 1, the valve 29 being closed, the control plate 39 resting upon the surface of the casting 19, and the pointed end of block 59 being disposed below the ball 48 which is carried by the end of plate 39. When combustion is continuing at the normal temperature the parts will occupy substantially the position shown in Fig. 5, the heat responsive element 51 being distorted so that the bar 54 is tipped up sufficiently to hold the pointed end of block 59 in engagement with the ball 48, thus holding control plate 39 in an inclined position and the valve 29 above its seat. On the other hand, if the temperature of the burner tip should become extraordinarily high due to some abnormal increase in the rate of fuel flow or due to the denuding of the boiler with which the burner tip is associated, heat responsive element 51 is further distorted so that the control beam 54 swings upwardly past the ball 48, the spring 47 being compressed to permit this action, the end of the beam 54 then occupies the position shown in Fig. 6. Since the ball 48 is thus released from engagement with the pointed end of the beam, the spring 30' is effective in automatically closing the valve 29 and interrupting combustion.

The plug 31 is provided with means automatically to interrupt the flow of fuel should combustion occur adjoining the plate 4 and thus cause an increase in the temperature of the outer portion of the burner assembly in-

cluding the casting 19. Thus safety means is provided to prevent continued combustion in case of backfiring. This type of device is more particularly disclosed and claimed in my copending application, Serial No. 507,843, filed January 10, 1931. The plug 31 has an enlarged head 82 which may be knurled to permit ready removal, and has an externally threaded body portion 83 which normally engages internal threads in the bore 30 at the top of casting 19. A cylindrical recess 85 within plug 31 receives a substantially cylindrical valve member 86 which may slide within the recess. A coiled compression spring 87 is disposed within a central bore 89 in the valve member 86 and engages the upper end of the cylindrical recess 85. The lower portion of the valve member 86 has a conical extension 90 or valve proper which may move into engagement with the mouth of passage 33 to interrupt flow of fuel into the chamber 30. Normally this valve is held in its open position by a heat responsive element 91 which may be substantially C-shaped and which has an end portion secured by a screw 92 in a circumferential groove 93 upon the inner portion of plug 31. The opposite side of plug 31 is cut away to provide a slot 94 through which a reduced end portion 95 of the heat responsive element 91 extends normally to engage a groove 96 in the valve member 86, thus normally locking the valve in its open position and holding the spring 87 under compression. Should the casting 19 become heated by combustion adjoining the plate 4, the heat sensitive element 91 expands so that its end portion 95 moves out of engagement with the recess 96 and the spring 87 is then effective in causing the valve portion 90 to engage the mouth of passage 33, thus interrupting fuel flow. Obviously the entire valve assembly including member 31, the valve member 86, and the spring 87 as well as the heat responsive element 91, may be removed as a unit to permit resetting when necessary.

In order to prevent removal of the burner from the support 2 as long as normal combustion is continuing or immediately thereafter, I provide a latch member 60 which is pivotally mounted upon a screw 60' (Fig. 4) at the inner face of plate 4. The latch member 60 has an inwardly beveled end portion or latch block 61 which normally extends through an opening 62 in the flange 5 on the plate 4 and a registering opening 63 in the annular flange 6 upon the support 2. The normal locking position of this latch is shown in Fig. 5, a flat face of the latch block 61 engaging the side of the slot 63 and thus locking the burner against removal from the support. In order to hold the latch in this position during conditions of normal combustion, I provide a leaf spring 67 secured to the lower part of the latch block and having its

end disposed beneath the block 45. A stud 68 projects downwardly from this block and has an enlarged head, the end of the spring 67 being disposed between the block and this head so that movement of the block 46 with the control plate 39 tends to cause the swinging of the latch member 60 about its pivot 60^a, whereby the latch block 61 may be swung upwardly into the recess or opening 63 when the 10 control plate 39 moves upwardly to its normal operating position, as shown in Fig. 5. On the other hand, if combustion is interrupted and the burner allowed to cool, the element 51 will flex sufficiently to cause lowering of the 15 bar 54 and the plate 39, and the latch swings to a position wherein it no longer projects into the opening 63, as shown for example in Fig. 4.

In order to permit initial ignition of fuel 20 issuing from the burner tube 9 at the burner tip, I provide an arrangement which permits the valve 29 to be held open manually independently of the action of the heat responsive element 51. For this purpose an angle 25 76 has one leg disposed in a recess in casting 19 beneath the plate 39 (Figs. 3 and 13) and has its other leg extending upwardly. Accordingly if the angle 76 is tipped by causing movement of its 30 vertical leg out of a vertical position, the plate 39 is tipped upwardly about its fulcrum recess 40 and the valve 29 accordingly is moved into an open position, thus it is only necessary to pull (or push) the upwardly extending portion of angle 76 in a lateral direction in order to cause the valve to open. When the burner is removed from the support 2 the valve 29 may be held open manually 35 in this manner and the mixture issuing from 40 the burner tip may be ignited. Since the latch block 61 is beveled the burner may then readily be reinserted in the support, the beveled latch block being disposed as shown in Fig. 7 as this occurs. Movement of the 45 latch block in this manner is permitted, due to the flexing of spring 67, despite the elevated position of block 45 and stud 68. Combustion may then be permitted to continue until the element 51 distorts sufficiently in 50 response to the heating of the burner tube to hold the plate 39 in its inclined position, thus being effective in holding valve 29 open independently of the manual control. The burner may then be reengaged with the 55 support 2.

A protective cage 100 of perforated sheet metal is normally disposed about the outer portion of the combustion apparatus being secured to the plate 4 by detachable elements 60 such as screws 101 (Fig. 2). This cage prevents undesirable tampering and protects the burner against undesirable drafts, which might cause backfiring. A slideable plunger 103 is carried by one side of the cage 100 and is adapted to engage the upwardly pro-

jecting lug of angle member 76 (Fig. 13), so that the valve 29 may be held open manually without necessitating removal of the cage. Suitable cam-like retaining elements 105 are pivotally secured by screws 106 to the outer 70 face of support 2 and are adapted to be swung to positions wherein they aid the latch 61 in holding the burner in normal position. In order to permit proper location of the burner in the support, an outstanding nub 120 may 75 be mounted upon the upper part of the support 2 and engage a suitable notch in the upper edge of plate 4. Thus the burner may readily be reinserted in its proper position, and the retaining elements 105 may be reengaged with the plate 4 firmly to hold the latter in place.

In the normal operation of apparatus of this character and when combustion is occurring at the desired temperature, the parts 80 may be in substantially the position shown in Fig. 5. Fuel such as gas flows upwardly through the supply duct 24 and the inlet passage 23 to the valve chamber 25, thence through passage 33, chamber 30 and vent 35 85 into the bushing 12 and through the burner tube 9 and the grid 10, combustion occurring at the outer end of the tube. Under these conditions the thermostatic element 51 will be so shaped that it holds the end of bar 54 upwardly in engagement with the ball 48, thus retaining the control plate in a tilted position and holding valve 29 open. Under these conditions, latch 61 is held in the recess 63, thus locking the burner in place so that it can not be removed from the support as long as normal combustion continues. If, however, combustion is interrupted the heat responsive element 51 will cool so that the pointed end of beam 54 lowers to the position shown in Fig. 1, thus permitting the control plate 39 to rest upon the surface of casting 19 and the valve 29 to be closed. The downward movement of plate 39 also is effective through spring 67 in swinging the latch member 60 so that the latch block 61 moves downwardly out of the recess 63. Under these conditions the burner can readily be slid out of engagement with the support after the cam elements 105 have been released. In case of abnormally high temperatures adjoining the burner tube, as, for example, when the boiler which is associated with the burner is denuded, the heat-sensitive element 51 is distorted sufficiently 105 to cause the pointed end of beam 54 to snap past ball 48 so that the control plate 39 returns to its inoperative position and the valve 29 is closed by spring 30. Fig. 6 shows such a position of the parts. Should backfiring occur so that combustion takes place adjoining the plate 4, the casting 19 may heat up sufficiently to cause the thermostatic element 91 to expand, thus releasing valve member 86 and permitting the automatic closing of valve 90, thereby interrupting further fuel 110 115 120 125 130

flow and consequently stopping combustion. Furthermore, under certain conditions of backfiring and combustion adjoining the plate 4 the thermostatic element 51 will become heated sufficiently to cause the beam 54 to assume the position shown in Fig. 6 so that the valve 29 is permitted automatically to close; in some cases, this may occur before the member 86 is released. Thus either the valve 29 or the valve 90 with their associated control means may be effective in interrupting combustion should backfiring take place.

When the burner has been removed from the support, it may be lighted when the angle member 70 is tipped by holding the plunger 103 inwardly. This permits the valve 29 to be held open independently of the thermostat 51; under these conditions the parts may be in the position shown in Fig. 7, the ball 48 being lifted out of contact with the pointed end of control beam 54. Thus the valve may be held open manually without causing distortion of the element 51. The valve is thus held open manually until the thermostat or heat responsive element 51 distorts sufficiently under heat so that it engages the ball 48 to hold the valve 29 in open position; thereupon the burner may be reinserted in the support, the spring 67 permitting the beveled face of latch block 61 to snap past the edge of the support and into the recess 63, Fig. 7 showing the position of the parts as the burner is thus being reinserted. The spring 67 permits this movement of the latch without necessitating the downward movement of the control plate 37 and the closing of valve 29.

Since the tube 9 and the hollow beam 56 are formed of thin sheet metal of low heat conductivity, and since the mica jacket 15 also has low conductivity, there is comparatively little flow of heat from the burner tip to the plate 4 and the casting 19 during normal operation of the burner; thus higher thermal efficiency is attained.

From the foregoing it is evident that I have provided a burner adapted to burn fluid fuel such as gas, which is particularly suited for employment in apparatus where combustion may continue for an indefinite period and where necessity for skilled or frequent attention is undesirable. A burner of this character is arranged automatically to interrupt combustion in case of inadvertently high temperatures at the burner tip, as well as in case of backfiring; furthermore removal of the burner from its support is prevented as long as normal combustion is occurring and thereafter until the burner has cooled off, thus permitting the escape of any unburned gas into the flue.

I claim:

1. Apparatus of the class described comprising a burner tube, a fuel duct connected to the burner tube, a valve in said duct, a spring tending to close the valve, a heat-re-

sponsive element adjoining the tube, control means actuatable by said element to hold the valve open in response to a normal operating temperature range, said element and control means being operative to release the valve when the temperature of the burner tube either rises above or falls below the normal operating range.

2. Apparatus of the class described comprising a support, a burner normally mounted within the support but being removable therefrom, said burner including a burner tube extending from the support and having an open end remote from the support where combustion normally occurs, a fuel supply duct connected to the burner tube, a valve associated with the supply duct, and movable between open and closed positions, control means including a heat-responsive element in heat transfer relation to said end of the burner tube, said means being operable in response to the temperature of the heat responsive-element to move the valve and hold it in its open position, a spring urging the valve toward its closed position, and latch mechanism to hold the burner within the support, said latch mechanism being maintained in locking position when the valve is thus maintained in its open condition.

3. Apparatus of the class described comprising a supporting part, a burner tube projecting from said part to provide a burner tip, a heat-sensitive element having an end in heat transfer relation to said tube, a valve, a valve casing, means yieldably urging the valve toward its closed position, and control means cooperating with the heat-sensitive element and valve to hold the valve open against the action of the first-named means when the burner tube is at a normal operating temperature range, but permitting the first-named means to close the valve when the burner tube temperature rises above or falls below said range.

4. Apparatus of the class described comprising a supporting part, a burner tube projecting from said part to provide a burner tip, a heat-sensitive element having an end in heat transfer relation to said tube, a valve, a valve casing, means yieldably urging the valve toward its closed position, a member secured to the opposite end of said element, a movable control part operatively associated with the valve, said member engaging said control part to hold the valve open in a normal operating temperature range, said member moving out of engagement with said control part in response to distortion of the temperature responsive element caused by a temperature either above or below said range, whereby the valve may close in response to either abnormally high operating temperatures or to interruption of combustion.

5. Apparatus of the class described, comprising a support, a burner part receivable

within said support, a burner tube projecting from said part to provide a burner tip, a heat-sensitive element having an end in heat transfer relation to said tube, a valve, a valve casing, means yieldably urging the valve toward its closed position, and a control member between the heat-sensitive element and valve to hold the valve open against the action of the first-named means when the burner tube is at normal operating temperature, but permitting the first-named means to close the valve when the burner tube temperature rises above or falls below said range, said member and said tube both being formed of material of low heat conductivity and having relatively thin walls, thus affording high resistance to heat flow from the burner tip.

6. Apparatus of the class described, comprising a support, a burner part receivable within said support, a burner tube projecting from said part to provide a burner tip, a heat-sensitive element having an end in heat transfer relation to said tube, a valve, a valve casing, means yieldably urging the valve toward its closed position, and control means between the heat-sensitive element and valve to hold the valve open against the action of the first-named means when the burner tube is at normal operating temperature, but permitting the first-named means to close the valve when the burner tube temperature falls below said range, a latch carried by the burner part to hold the latter upon the support, said latch being operably associated with said control means and being actuated thereby to hold the burner part locked within the support while the valve is being held open.

7. Apparatus of the class described, comprising a supporting part, a burner tube projecting from said part to provide a burner tip, a heat-sensitive element having an end in heat transfer relation to said tube, a valve, a valve casing, means yieldably urging the valve toward its closed position, control means between the heat-sensitive element and valve to hold the valve open against the action of the first-named means when the burner tube is at normal operating temperature, but permitting the first-named means to close the valve when the burner tube temperature falls below said range, and manually operable means to hold the valve open irrespective of the condition of the control means.

8. Apparatus of the class described, comprising a support, a burner part receivable within said support, a burner tube projecting from said part to provide a burner tip, a heat-sensitive element having an end in heat transfer relation to said tube, a valve, a valve casing, means yieldably urging the valve toward its closed position, control means between the heat-sensitive element and valve to hold the valve open against the action of the first-named means when the burner tube is

at normal operating temperature, but permitting the first-named means to close the valve when the burner tube temperature rises above or falls below said range, a latch carried by the burner part to hold the latter upon the support, said latch being operably associated with said control means and being controlled thereby to hold the burner part locked within the support while the valve is being held open, and manually operable means to hold the valve open irrespective of the condition of the control means, the latch having a beveled surface to engage the support, and a spring between the latch and control means, whereby the latch may be snapped into its locking position while the valve is being held open.

9. Apparatus of the class described, comprising a support, a burner part receivable within said support, a burner tube projecting from said part to provide a burner tip, a heat-sensitive element having an end in heat transfer relation to said tube, a valve, a valve casing, means yieldably urging the valve toward its closed position, a member secured to the opposite end of said element, a movable control part operatively associated with the valve, said member engaging said control part to hold the valve open in a normal operating temperature range, said member moving out of engagement with said control part in response to distortion of the temperature responsive element caused by a temperature either above or below said range, whereby the valve may close in response to either abnormally high operating temperatures or interruption of combustion, manually operable means to move the control part and hold the valve open irrespective of the condition of the control means, a latch on the burner part to lock the latter in engagement with the support, and a spring between the control part and latch, whereby the latter is normally retained in its locking position while the control part holds the valve open, the latch having a beveled surface to engage the support, the spring flexing to permit the latch to snap into engagement with the support when the burner is brought into engagement with the support, even if the control part is in a position to hold the valve open, the latch locking the burner part against removal from the support when the control part is in said position.

10. Apparatus of the class described comprising a support, a burner on the support, releasable means for retaining the burner on the support, a supply valve for the burner, a temperature-sensitive member movable in response to temperatures of the burner, and means effective when the temperature-sensitive member is subjected to substantially normal operating temperatures for locking the

releasable means in position to retain the burner on the support.

11. Apparatus of the class described comprising a support, a burner on the support, releasable means for retaining the burner on the support, a supply valve for the burner, a temperature-sensitive member movable in response to temperatures of the burner, means effective when the temperature-sensitive member is subjected to substantially normal operating temperatures for locking the releasable means in position to retain the burner on the support and for holding the supply valve open.

15 12. Apparatus of the class described comprising a support, a burner on the support, a supply valve for the burner, means tending to close the supply valve, and means responsive to substantially normal operating temperatures for locking the burner on the support, said means retaining the burner locked on the support after combustion has been interrupted to permit dispersion of unburned gases before the burner can be removed from the support.

13. The combination with a burner and means for supplying fuel thereto, of means responsive to substantially normal operating temperatures of the burner for maintaining the supply of fuel, said means being effective on cooling of the burner for interrupting the supply of fuel, and means responsive to temperatures due to abnormal operating conditions for interrupting the supply of fuel.

35 14. Apparatus of the class described comprising a support, a burner on the support, releasable means for retaining the burner on the support, and temperature responsive means effective during normal operation for locking the releasable means in position to retain the burner on the support, the temperature responsive means also being effective to lock the releasable means for a sufficient time after a period of operation of the burner to allow unburned gases to escape therefrom.

50 15. Apparatus of the class described comprising a support, a burner on the support, releasable means for retaining the burner on the support, means for controlling the delivery of fuel to the burner, and temperature responsive means effective during normal operation to lock the releasable means in position to retain the burner on the support and to actuate the control means to maintain the delivery of fuel to the burner, the temperature responsive means also being effective to lock the releasable means for a sufficient time after a period of operation of the burner to allow unburned gases to escape therefrom.
